UNITED STATES PATENT OFFICE

2,193,187

LAST JACK

William L. Baxter, Marblehead, Mass., assignor to United Shoe Machinery Corporation, Borough of Flemington, N. J., a corporation of New Jersey

Application April 7, 1939, Serial No. 266,521

7 Claims. (Cl. 12—15.1)

The present invention relates to last jacks and is illustrated herein as embodied in a jack adapted for use in disassembling a last having separable fore and heel parts without disturbance of the forepart of a shoe made on the last.

In one type of such lasts, as exemplified by that disclosed in Letters Patent No. 2,054,935, granted on September 22, 1936, in the name of J. B. Hadaway, the fore and heel parts are connected by a locking bolt and a sliding joint so constructed that when the bolt is moved into its inoperative position the last parts may be moved with respect to each other in such a direction that the forepart and heel part may be moved freely away from each other preparatory to the removal of the forepart of the last from the shoe.

The above-mentioned Hadaway patent also discloses a jack adapted for use in disassembling a last of the above type, the jack being provided with two separately operated instrumentalities one of which moves the locking bolt into its inoperative position and the other of which presses upon the forepart to slide it with respect to the heel part. It is apparent that the movement of the locking bolt will be frictionally impeded or may possibly be prevented by the premature operation of the forepart pressing means; and that an operator's production is impaired by any time lag between the arrival of the locking bolt in its operative position and the beginning of the application of pressure against the forepart. Accordingly, it is a principal object of this invention to provide an improved jack of the above type which can be easily and quickly operated and which will insure the optimum sequence in the operation of the locking bolt and the application of pressure against the forepart.

To this end, the invention provides manually operated means for operating the locking bolt and pressing upon the forepart of a last of the above type, in timed relation and in the order named, whereby the forepart of the last and the shoe thereon are moved relatively to the heel part after the last parts have been unlocked.

As herein illustrated, the above-mentioned manually operated means includes a lost motion device which causes the operation of the forepart pressing means to be delayed during such movement of the bolt as is necessary to unlock the last parts, but immediately thereafter actuates the pressing means to slide the forepart on the heel part.

Another feature of the invention resides in the provision of means for holding the last on the jack against the pressure of the forepart pressing

means which tends to push the last off the jack.

These and other features of the invention comprising certain combinations and arrangements of parts will be apparent from the following description of a preferred embodiment of the invention shown in the drawing, in which:

Fig. 1 is a view in side elevation of a jack embodying the invention, the heel part of a last on the jack, and a lasted shoe being shown in section;

Fig. 2 is an end elevation of the joint between the fore and heel parts of the last of Fig. 1 looking toward the forepart perpendicular to the joint surfaces;

Fig. 3 is a view in side elevation, partly in section, illustrating the jack and last after the forepart has been slid upon the heel part, and

Fig. 4 is a front elevation of the jack as viewed in the direction of the arrow of Fig. 1.

The last, which will be described herein only to the extent which is necessary for an understanding of the use of the illustrated jack, and which is similar to that disclosed in the above-mentioned Hadaway patent, comprises a forepart

10 and heel part 12 having plane joint surfaces 14 on which the fore and heel parts are arranged

20 to slide at such an angle that the heel parts of the last and of a lasted shoe thereon may be freely separated as will be clearly understood from a comparison of Figs. 1 and 3. The heel part 12 of the last comprises a heel plate 16, a thimble 17, and a bonding plate 18, all of which are effectually integral with each other, the latter having a heightwise extending slot 20 formed

25 therein. Studs 22 carried by a block 23 firmly embedded in the forepart 10 and which closely fit between the sides of the slot 20 are provided

30 with heads 24 arranged to overlie portions of the bonding plate 18 contiguous to its slot so as to hold the joint surfaces 14 of the last parts in contact with each other. To permit the last parts to be readily separated from each other upon being moved into the relation in which they

35 are illustrated in Fig. 3, the slot 20 is provided with two circular enlargements 26, 27 of sufficient size and so spaced as to admit freely the heads

40 24 of the studs 22.

In order to prevent any sliding action between the last parts when they are in their assembled

45 relation, a locking bolt 28 slidably mounted in the block 23 is arranged normally to project beyond the joint surface 14 of the forepart into the enlargement 27 in the bonding plate 18. The

50 bolt 28 is urged outwardly of the block 23 by a

spring 30, the ejection of the bolt from the block being prevented by shoulders thereon.

It will now be understood that the last is assembled by putting the fore and heel parts together, the bolt 28 being forced against the pressure of the spring 30 into the block 23 by the bonding plate 18 and the heads 24 of the studs 22 being inserted through the enlargements 26, 27. The fore and heel parts are then slid with respect to each other until the bolt 28 snaps into the enlargement 27 whereby any further sliding movement of the last parts is positively prevented until the bolt 28 is again moved into its inoperative position.

15 The illustrated jack for unlocking and separating the last parts comprises a frame 32 carrying at its upper portion a jack pin 34 having a dovetailed member 36 at its base received in a slot in the frame 32 to permit the pin to be readily moved laterally of the last so that the bolt 28 and forepart cone portion of both right and left lasts occupy substantially the same position, respectively. A last when mounted on the pin 34 is so situated that the bolt 28 is directly opposite to a member 38 pivotally mounted at 49 on a lever 42 which is mounted to swing on a fulcrum 44 in such a direction as to move the bolt 28 axially out of contact with the bonding plate 18. The lever 42 is connected by a link 46 to a plate 48 which is fixed to a shaft 50 rotatably mounted in the frame 32. The shaft 50 is operated by a rod 52, the upper end of which is pivoted to an arm 54 which is pinned to the outer end of the shaft 50. The rod 52 may be operated by a treadle or by any other suitable means and upon being released by the operator is returned to its uppermost position by a spring 56 connecting it with the frame 32.

40 The forepart is slid with respect to the heel part, immediately after the bolt 28 has been moved into its inoperative position, by a sliding plunger 58 having a cushioned head 60 adapted to engage the cone portion of the forepart adjacent to its joint surface 14, the operation of this 45 plunger being delayed during the movement of the bolt 28 into its inoperative position by a lost motion device comprising a link 62 pivoted at one end to the plunger at 64 and carrying at its other end a pin 66 which is received in a 50 slot 68 in the plate 48. Thus, when the plate 48 is swung in a counterclockwise direction from its position as illustrated in Fig. 1 the plate moves freely with respect to the pin 66 until the lower end of the slot 68 abuts the pin 66, the 55 bolt 28 at this time having been moved into its inoperative position. Further movement of the plate 48 beyond this point causes the plunger 58 to be moved upwardly to press against the forepart and slide it heightwise of the heel part until the studs 22 are alined with the enlargements 26, 27.

60 Just before the head 60 begins to exert pressure against the forepart, a latch 70 pivoted at 72 on the frame 32 is swung to cause a detent 74 65 on the latch to overlie a shoulder 75 on the bonding plate 18 to prevent the upward thrust of the head 60 from pushing the heel part of the last off the pin 34. The latch 70 is thus operated by a link 76 which is connected to the 70 latch by a ball and socket joint and is pivoted at 77 to the lever 42.

To insure against the sliding movement of the forepart 10 being impeded by the member 38, the latter is permitted to yield about its pivot 40 on the lever 42 by a spring 78, the member 38 thus

being arranged to swing in a counterclockwise direction when it is engaged by the heads 24 of the studs 22.

To summarize briefly the operation of the illustrated jack, in disassembling a last thereon, the lowering of the rod 52 causes the plate 48 to be swung in a counterclockwise direction which results in the lever 42 being swung so as to cause the member 38 to push the bolt 28 out of engagement with the bonding plate 18. At the same time, the latch 70 is swung in a clockwise direction bringing the detent 74 opposite to the shoulder 75 on the bonding member whereby the heel part 12 is positively prevented from being moved upwardly with respect to the jack pin 34. After the bolt 28 has been moved into its inoperative position, the pin 66 then being substantially in engagement with the lower end of the slot 68, the head 60 begins to exert upward pressure on the forepart 10 which results in the forepart being slid upon the heel part until the studs 22 are alined with the enlargements 26, 27. It is evident that the forepart 10 of the last, with the shoe thereon, can then easily be moved from the heel part 12 and that the forepart may be freely removed from the shoe thereby completing the delasting of the shoe.

Having thus described my invention, what I claim as new and desire to secure by Letters Patent of the United States is:

30 1. A last pulling jack for removing from a shoe a last having a removable heel part and a forepart with a sliding joint between them and a locking bolt to prevent such sliding action, said jack having means for holding the heel part, means for moving the locking bolt to inoperative position, means for pressing upon the forepart to slide the forepart upon the heel part, and manually operated means for operating the said means for moving the bolt and pressing upon the forepart in timed relation, whereby the forepart and a shoe on the last may be moved relatively to the heel part after the locking bolt has been moved to inoperative position.

35 2. A last pulling jack for removing from a shoe a last having a removable heel part, a forepart with a sliding joint between them and a locking bolt to prevent such sliding action, said jack having means for holding the heel part, means for moving the locking bolt to and holding it in inoperative position, means for sliding the forepart upon the heel part, and a lost motion connection between the two last-named means for causing them to be operated in the order named successively to unlock the last parts and to move the forepart relatively to the heel part.

40 3. A last pulling jack for removing from a shoe a last having a removable heel part, a forepart with a sliding joint between them and a locking bolt to prevent such sliding action, said jack having means for holding the heel part, means for moving said bolt into inoperative position, said means comprising a manually operated member having a slot, a plunger adapted to engage the forepart and slide it on the heel part, and a link extending between said slot and plunger whereby said plunger is actuated to move the forepart relatively to the heel part after said bolt has been moved into its inoperative position.

45 4. A last pulling jack for removing from a shoe a last having a removable heel part, a forepart with a sliding joint between them and a locking bolt to prevent such sliding action, said

jack having means for holding the heel part, means for moving the locking bolt to, and holding it in, inoperative position, means for pressing upon the forepart in the vicinity of the joint to displace the forepart relatively to the heel part, and manually operated means for operating the two last-named means in the order named to unlock the last and to displace the forepart thereof and a shoe thereon relatively to the heel part while holding the locking bolt in inoperative position.

5. A last pulling jack for removing from a shoe a last having a heel part and forepart which are separable and a sliding joint between the last parts including a locking bolt to prevent such sliding action, said jack having a pin upon which the heel part is mounted, a plunger adapted to be moved into engagement with the forepart to slide it upon the heel part, a latch for holding the heel part against displacement on said pin, a member connected to said latch and mounted and arranged to move said bolt into inoperative position, and means for operating said member and plunger in succession, thereby to move the forepart relatively to the heel part after the locking bolt has been moved into its inoperative position.

6. A last pulling jack for removing from a shoe a last having a removable heel part, a forepart with a sliding joint between them and a locking bolt to prevent such sliding action, said jack having means for holding the heel part, a lever pivoted on the jack frame and having one end ar-

ranged, when the lever is swung, to contact with the locking bolt and move it to inoperative position, a manually operated member connected to the lever to swing the lever as stated, a pushing member arranged to press upon the forepart to slide it upon the heel part when unlocked, and a lost motion connection between the manually operated member and the pushing member whereby the forepart is so slid upon the heel part after the lever has moved the locking bolt to inoperative position.

7. A last pulling jack for removing from a shoe a last having a removable heel part, a forepart with a sliding joint between them and a locking bolt to prevent such sliding action, said jack having means for holding the heel part, a lever pivoted on the jack frame and having one end arranged, when the lever is swung, to contact with the locking bolt and move it to inoperative position, a manually operated swinging member linked to the lever to operate the lever and having a slot, a pushing member arranged to slide in the jack frame and to push upon the forepart when so slid thereby to move the forepart relatively to the heel part, and a link extending between the pushing member and the slot, whereby the manually operated swinging member will pick up the pushing member after it has operated the lever to render the locking bolt inoperative and to displace the forepart and a shoe thereon relatively to the heel part.

WILLIAM L. BAXTER.
